In their attorney, Charles N. Goodman

UNITED STATES PATENT OFFICE.

WALTER E. BARTLETT, OF LOWELL, AND JOHN H. TRAYNE, OF GROTON, MASSACHUSETTS.

ENVELOP-SEALING DEVICE.

1,275,832.

Specification of Letters Patent. Patented Aug. 13, 1918.

Application filed October 19, 1917. Serial No. 197,397.

To all whom it may concern:

Be it known that we, WALTER E. BARTLETT and JOHN H. TRAYNE, citizens of the United States, residing, respectively, at Lowell and 5 Groton, in the county of Middlesex and State of Massachusetts, have invented new and useful Improvements in Envelop-Sealing Devices, of which the following is a specification.

10 This invention relates to a device for moistening the adhesive material upon the flap of an envelop and for sealing the same after it is moistened.

The object of the invention is to provide 15 a neat and compact device whereby the adhesive material upon the flap of an envelop may be quickly moistened and the said flap sealed to the body portion of the envelop, and to these ends the invention consists in 20 the combination and arrangement of parts set forth in the following specification and particularly pointed out in the claims thereof.

Referring to the drawings:

25 Figure 1 is a plan view of our improved envelop sealing device.

Fig. 2 is a sectional elevation taken on line 2—2 of Fig. 1.

Like numerals refer to like parts throughout the several views of the drawings.

In the drawings, 5 is a receptacle for 30 liquid, 6 is a top for said receptacle, preferably corrugated at 7 and provided with perforations 8. A moistening pad 9 rests 35 upon the top 6 and its opposite edges 10 project through slots 11 in said top and into the interior of the receptacle.

A folder blade 12 extends upwardly from 40 the rear edge of the receptacle and preferably at an angle thereto, and upon this folder blade there rests the front edge of a supporting table 13, the rear end of said supporting table being provided with legs 14 adapted to rest upon the same stationary 45 support that the receptacle 5 rests upon. The work supporting table 13 is provided with ears 15 which extend over and contact with the folder blade 12.

The cover 6 is preferably hinged to the 50 receptacle 5 at 16 in order that the interior of the receptacle 5 may be replenished with water when desired.

The general operation of the device is as follows: An envelop 17 is placed in a hori-

zontal position, as illustrated in Fig. 2, with 55 the flap 18 extended and with the adhesive material on the flap contacting with the moistening pad 9. The envelop is then raised and pushed backwardly into the position illustrated in dotted lines, Fig. 2, and 60 the edge of the flap 18 contacting with the folder blade 12 causes the said flap to be folded under the body portion of the envelop as illustrated in dotted lines, Fig. 2. A further motion of the envelop backwardly 65 brings said envelop and the flap thereof upon the table 13 and the envelop is then pressed down so as to bring the moistened adhesive material upon the flap in contact with the body portion of the envelop. 70 It is then rubbed slightly to more perfectly bring the flap into contact with the body portion of the envelop and the envelop is thus sealed.

When it is desired to pack the device into 75 small compass, in order that the same may be shipped or for any other reason, the table 13 is detached from the receptacle by disconnecting the ears 15 from the folder blade 12 and placing the same in the position 80 illustrated in dotted lines, Fig. 2.

Having thus described our invention, what we claim and desire by Letters Patent to secure is:

1. An envelop sealing device having, in 85 combination, a receptacle for liquid, a perforated top for said receptacle, a pad extending across said perforated top and projecting therethrough into the interior of said receptacle, a folder blade extending 90 upwardly along one edge of said receptacle and an envelop supporting table extending from the upper edge of said folder blade away from said pad.

2. An envelop sealing device having, in 95 combination, a receptacle for liquid, a pad extending over the top of said receptacle and projecting downwardly through said top into the interior thereof and a folder blade extending upwardly from said receptacle adjacent one edge of said pad.

3. An envelop sealing device having, in 105 combination, a receptacle for liquid, a pad extending over the top of said receptacle and projecting downwardly through said top into the interior thereof, a folder blade extending upwardly from said receptacle adjacent one edge of said pad and an en-

velop supporting table detachably fastened to said folder blade and extending from the upper edge thereof away from said pad.

4. An envelop sealing device having, in combination, a receptacle for liquid, a pad extending over the top of said receptacle and projecting downwardly through said top into the interior thereof, a folder blade extending upwardly from said receptacle

10 adjacent one edge of said pad, an envelop supporting table detachably fastened to said folder blade and extending from the upper edge thereof away from said pad and legs projecting downwardly from said folder

15 blade and adapted to rest upon a stationary support.

5. An envelop sealing device having, in combination, a receptacle for liquid, a flat

horizontal moistening pad extending over the top of said receptacle and arranged to 20 be moistened by the liquid in said receptacle, a stationary folder blade extending upwardly from the rear side of said receptacle and at an acute angle thereto and a horizontal envelop supporting table extending from 25 the upper edge of said folder blade away from said pad.

In testimony whereof we have hereunto set our hands in presence of two subscribing witnesses.

WALTER E. BARTLETT,
JOHN H. TRAYNE.

Witnesses:

CHARLES S. GOODING,
SYDNEY E. TAFT.
